UNITED STATES PATENT OFFICE

2,294,307

DOOR LOCK

Otto C. Larson, Brooklyn, N. Y.

Application October 16, 1940, Serial No. 361,402

11 Claims. (Cl. 70—143)

This invention relates to door locks, and particularly to a lock having means providing key operation of the lock into deadlock position externally of a room or compartment, thus preventing an unauthorized person, gaining access to a room or compartment through a window or other entrance, from leaving the compartment through the door controlled by said lock; and the object of the invention is to provide a lock of the character described wherein the lock bolt may be moved into open position by either the knob or the key actuated mechanism when the bolt is in normal locked position, and further whereby the bolt may be moved into the deadlock position and opened from the deadlock position solely by the key operating mechanism of the lock; a further object being to provide a lock of the character described employing two bolt engaging and operating elements rotatable about the lock spindle individually and collectively in controlling the operation of the lock and in retaining the inner knob against rotary movement to release the bolt when the latter is in deadlocked position; and with these and other objects in view, the invention consists in a lock construction of the class and for the purpose specified, which is constructed as more fully herein-after described, and which is defined in the appended claims.

The invention is fully disclosed in the following specification, of which the accompanying drawing forms a part, in which the separate parts of my improvement are designated by suitable reference characters in each of the views, and in which:

Fig. 1 is a diagrammatic sectional view through a part of a door and door frame showing my invention applied to one form of lock.

Fig. 2 is a partial section on the line 2—2 of Fig. 1.

Fig. 3 is a partial section on the line 3—3 of Fig. 2.

Fig. 4 is a cross section substantially on the line 4—4 of Fig. 2.

Fig. 5 is a view substantially similar to Fig. 2 showing only a part of the construction and with parts in a different position; and

Fig. 6 is a view similar to Fig. 5 showing the parts in deadlock position.

In Fig. 1 of the drawing, 10 represents a part of a door frame to which the bolt receiving keeper 11 of the lock is secured. At 12 is indicated part of a door, apertured as seen at 13 to receive the cylinder 14 of a more or less conventional cylinder lock, and into which cylinder a conven-

tional key 15 is insertable to control the operation of the lock spindle 16. The lock spindle 16 extends into the casing 17 as well as into the tubular portion 18 of the inner knob 19 which controls the operation of the bolt 20 from the inside of the room or compartment controlled by the door 12. On the inner surface of the lock casing 17 is a removable plate 21, and screws 22 are passed through this plate and into extensions 23 on the cylinder 14 in supporting the cylinder in position within the aperture 13.

The bolt 20 has an offset portion 24 within the lock casing, operating upon a rod 25 arranged between two posts 26a of a slide 26 mounted and guided in the casing 17 as seen in Fig. 2. The extension 24 is free to slide on the rod against the action of a spring 27 arranged thereon in the automatic latching of the bolt 20 in the operation of closing the door. The spring serves to hold the bolt in the normal protracted position seen in Fig. 1. On the offset portion 24 is a rearwardly extending plate 28 which is arranged between the rod 25 and the slide 26. This plate has an extension or raised portion 29 having a rounded or cam surface 30 and an opposed straight surface 31.

On the slide 26 is a cam surface 32, by means of which the bolt may be retracted from an extended or locked position. These various lock mechanisms as described form no particular part of the present invention and are described to give the general assemblage of mechanism necessary to understand the new structural features which form the subject matter of the present invention. Other details of the lock are omitted simply to avoid unnecessary detail description.

Another conventional part of the lock comprises the lock spindle receiving sleeve 33 which is freely rotatable in the detachable plate 21, and has a slot for receiving the spindle 16, and also carries at its inner end a ring 34 having projecting lugs 35. The lugs 35 normally operate in conjunction with a single actuating sleeve arranged upon the portion 18 of the knob 19, but instead of employing this usual mechanism or sleeve, I employ two lock control elements 36 and 37. These elements comprise two substantially disc-like members, one having an extending arm 38 for operative engagement with the extension 29, and the other having a corresponding arm 39, a conventional hook arm 40, and a lug 41. The latter represents an element substantially similar to the conventional element of this type and kind employed in other locks. The

element 36 is keyed to the sleeve 18 by a pin or otherwise as seen at 42, whereas the element 37 is retained against displacement from the sleeve but is free to rotate thereon and with respect to the element 36. The lug 41 extends in the direction of the two lugs 35 and is arranged in the path of rotation of said lugs so that rotation of the key actuated sleeve 33 will operate to move the lock bolt 20 from the normal latching or lock position shown in Fig. 1 into open position; further, to move the bolt 20 into the extended or deadlock position shown in Fig. 6 and to then withdraw the bolt from the deadlock position in the manner illustrated in Fig. 5. The element 36, however, which is actuated through the knob 19, is only capable of withdrawing the bolt 20 from the position shown in Fig. 1 to an open position. In the lock casing 17 is arranged a stop screw 43 which checks the movement of the element 37, particularly when the parts are in the position shown in Fig. 6 of the drawing.

It will be understood that locks of the type and kind under consideration in addition to being applicable to doors controlling rooms or compartments, entrances to buildings, homes and the like, are also applicable to various types and kinds of apparatus, and particularly will be useful in conjunction with motor vehicles where the doors of the vehicles may be all locked through the medium of lock mechanisms of the general type under consideration. It will thus be apparent that the mere breaking of a window of the vehicle will not give access to the interior of the vehicle, except through the broken window, which act is bound to be deduced in the event of the attempted theft of the car. In other words, generally speaking, the movement of a bolt into deadlock position through the key actuated mechanism externally of any compartment will render it impossible to open the door from the interior of the compartment whereas when the lock is in its normal position, in other words when not in the deadlock position, the door may be opened and closed from the interior as in other more conventional locks.

In the normal position of the lock, as is shown in Fig. 1 of the drawing, as well as in Fig. 2, the bolt 20 may be drawn inwardly to open the door, either through the actuation of the key operated element 37 externally of the door, or by the knob 19 internally of the door. Furthermore, the bolt 20 may move inwardly and outwardly automatically in the operation of closing the door as in other lock constructions. When it is desired to move the bolt 20 into the deadlock position shown in Fig. 6 of the drawing, the key 15 is inserted into the cylinder and the element 37 is rotated from the position shown in Fig. 2 into the position shown in Fig. 6. In the latter position, the end of the arm 38 is brought beneath a straight surface 29a on the extension 29, as will appear in Fig. 6 of the drawing, thus preventing rotation of the knob 19 in bolt withdrawing direction. It will appear, however, that upon inserting the key 15 into the lock, the element 37 may be rotated to return the bolt 20 first to the position shown in Figs. 1 and 2 by engagement of the hook-shaped arm 40 with the surface 32, and on continuing this rotary movement, the arm 39 of the element 37 will engage the extension 29 and draw the bolt 20 inwardly to unlocked position as is indicated in Fig. 5 of the drawing.

In various types and kinds of locks means are

usually provided to support the bolt in the inwardly drawn or unlocked position, but these means have been omitted in order to simplify the present illustration, bearing in mind that these things in themselves form no part of the present invention, and furthermore on different types and kinds of apparatus, different means are employed; particularly when the locks are incorporated in conjunction with handle members 5 members controlling door operation. It will of course be apparent that the lugs 35 cooperate with the upstanding lug 41 on the element 37 in controlling the key operation of this element, as will appear from a consideration of Figs. 2, 5 and 6 of the drawing.

The ring 34 may be said to be a clutch member placing the spindle 16 in operative engagement with the disc-like element 37 by engagement of the lugs 35 of said clutch with the lug 41 on said element. It will also appear from the lock construction disclosed that the two bolt actuating elements 36 and 37 rotate with respect to a common axis; that is to say, around the spindle 16 or the sleeve 18 of the knob 19.

Having fully described my invention, what I claim as new and desire to secure by Letters Patent, is:

1. A lock of the class described comprising a casing, a bolt movable into and out of the casing, a key actuated spindle, a manually operated knob, two bolt actuating elements, one actuated by said knob and the other by said spindle, both of said elements operatively engaging the bolt to draw the bolt inwardly into unlocked position, the spindle actuated element only, operatively engaging the bolt to move the same into and out of deadlock position; said elements comprising disc-like members rotatable about a common axis, each member having an arm operatively engaging said bolt, and one of said members including a second arm engaging the bolt to move the same into and out of deadlock position.

2. A lock of the class described comprising a casing, a bolt movable into and out of the casing, a key actuated spindle, a manually operated knob, two bolt actuating elements, one actuated by said knob and the other by said spindle, both of said elements operatively engaging the bolt to draw the bolt inwardly into unlocked position, the spindle actuated element only, operatively engaging the bolt to move the same into and out of deadlock position, said elements comprising disc-like members rotatable about a common axis, each member having an arm operatively engaging said bolt, one of said members including a second arm engaging the bolt to move the same into and out of deadlock position, a projecting lug on the last mentioned member, and a clutch plate keyed to the spindle and operatively engaging the lug on said last mentioned member.

3. A lock of the class described comprising a casing, a bolt movable in the casing to be extended through one wall thereof, two disc-like actuating elements in the casing rotatable about a common axis in operatively engaging the bolt to move the same into inoperative position, keyless means for operating one of said elements, key actuated means for actuating the other of said elements, said last named means comprising a clutch ring, and means whereby the rotation of said ring in one direction will actuate the bolt to extend the same into deadlock position.

4. A lock of the class described comprising a casing, a bolt movable in the casing to be ex-

tended through one wall thereof, two disc-like actuating elements in the casing rotatable about a common axis in operatively engaging the bolt to move the same into inoperative position, keyless means for operating one of said elements, key actuated means for actuating the other of said elements, said last named means comprising a clutch ring, means whereby the rotation of said ring in one direction will actuate the bolt to extend the same into deadlock position, and means rendering the first named element inoperative when the bolt is in deadlock position.

5. A lock of the class described comprising a casing, a bolt movable inwardly and outwardly through the casing, two bolt actuating elements rotatable about a common axis, manually actuated means for operating one of said elements for moving the bolt into the casing into unlocked position, key actuated means operating the other of said elements, and said last named means including dual means engaging said bolt for selectively retracting said bolt to unlocked position and projecting the same to deadlock position.

6. A lock of the class described comprising a casing, a bolt movable inwardly and outwardly through the casing, two bolt actuating elements rotatable about a common axis, manually actuated means for operating one of said elements for moving the bolt into the casing into unlocked position, key actuated means operating the other of said elements, said last named means including dual means engaging said bolt for selectively retracting said bolt to unlocked position and projecting the same to deadlock position, and cooperating means on said bolt and first named element, whereby movement of the bolt into deadlock position will move said element out of actuating engagement with said bolt.

7. A lock of the class described comprising a casing, a bolt movable inwardly and outwardly through the casing, two bolt actuating elements rotatable about a common axis, manually actuated means for operating one of said elements, key actuated means for operating the other of said elements, means on said last named element engaging said bolt for moving the same into unlocked position, other means on said element engaging said bolt for moving the same into deadlock position, and said last named

means in the normal locked position of the bolt forming a stop preventing movement of the bolt into deadlock position by said manually actuated means.

5 8. In a lock having an automatically actuated latch bolt and independent key operated and manually operated means for moving the bolt into inoperative position, a pair of bolt actuating elements, one element being actuated 10 through said manually operated means and the other through said key operated means, and means on said last mentioned element directly engaging said bolt to extend the bolt into deadlock position and to return the bolt from deadlock to normal position.

9. The combination with a door lock having manual means for moving the bolt of the lock into inoperative position from the inner side of a door, of key actuated means independent of said first named means for operating said bolt at the external side of the door, said key actuated means including an element having a projecting member for engagement with said bolt to move the same into open position, other means on said element cooperating with said bolt to move the same into and out of deadlock position from the external side of the door, and said last named means further cooperating with said bolt to prevent movement of the bolt to deadlock position by actuation of said first named means.

10. A lock of the class described comprising a casing, a bolt movable in the casing to be extended through one wall thereof, two disc-like actuating elements in the casing rotatable about a common axis and operatively engaging the bolt to move the same into inoperative position, keyless means for operating one of said elements, key actuated means for operating the other of said element, and said last named element including means directly engaging said bolt for moving the bolt into deadlock position.

11. The combination with a lock having a latch bolt, of two bolt actuating elements arranged side by side and operatively engaging the bolt to move the same into unlocked position, independent means for actuating said elements, and at least one of said elements directly engaging said bolt for extending the bolt into deadlock position and for withdrawing the bolt from said deadlock position.

OTTO C. LARSON.
